Bartlett & Brownell

UNITED STATES PATENT OFFICE.

RICHARD H. COOK, OF FALL RIVER, MASSACHUSETTS, ASSIGNOR TO THE AMERICAN THREAD COMPANY, OF JERSEY CITY, NEW JERSEY, A CORPORATION OF NEW JERSEY.

CREEL.

1,180,284.

Specification of Letters Patent. Patented Apr. 25, 1916.

Application filed July 26, 1915. Serial No. 41,880.

To all whom it may concern:

Be it known that I, RICHARD H. COOK, a citizen of the United States, residing at Fall River, Bristol county, Massachusetts, have invented certain new and useful Improvements in Creels, of which the following is a full, clear, and exact description.

My invention relates to improvements in creels for holding cones and the like containing thread to be wound upon bobbins and the like, such for instance as creels for use upon twisters and has for its object to increase the capacity of present twister frames; to prevent loss due to stoppage; to prevent the necessity of supplying yarn holding bobbins before they are exhausted; to prevent the ends of running out bobbins from lashing the threads or yarns on either side, and further to permit the adding of a further supply without stopping the machine, and to avoid double ply knots or adjacent knots in the threads from any creel.

The following is a description of an embodiment of my invention, reference being had to the accompanying drawings, in which,

Figure 1 shows an end view of a plurality of creels, guide rods, water trough and rolls, one of the creels being moved into a forward position for the purpose hereinafter stated; Fig. 2 shows a rear view of the same with the two creels in vertical position; Fig. 3 shows a plan view with all but one of the creels removed, that creel being shown in section on the line 3—3, Fig. 1.

Referring more particularly to the drawings, 1 is the frame of a twister machine carrying a series of bobbins provided with the ordinary spinning rings, etc., (not shown).

2 is one of a series of brackets supported by the frame and in turn supporting the rod 3, constituting a support for the creels. This support carries a series of creels, the same being movable thereon so that they can be placed in a vertical position or can be moved to a forward position. The movement of the creel is preferably obtained by pivoting the base thereof upon the rod 3.

4 is the base of the creel, movably journaled upon the rod 3. This base is provided with an upward projection 5 and the bracket is provided with an upward projection 6. This upward projection 6 carries a spring-pressed ball or lock, which engages one of

two recesses 7 in the upward projection from the creel base, holding the creel base in either the horizontal position shown by the first creel in Fig. 1, so that the creel is vertical, or in an inclined 60 position as shown by the rear creel of Fig. 1, so that the creel will be forwardly inclined. Carried by the base 4 are two upwardly extending rods or carriers 8 which are connected at their upper ends by a 65 bracket 9. These rods are provided with arbors 10 attached thereto and adjustable thereon so that they may be placed in positions determined by the length of the cones to be used. These arbors are provided with 70 forwardly and rearwardly extending arms, each of which carries means for supporting a cone thereon.

11—11' are two cones supported by the lower arbor and 12—12' are two cones supported by the upper arbor, these cones being wound in any manner so that the thread is easily unwound therefrom without requiring the cones themselves to be revolved. Above the lower set of cones is a pigtail 75 and guide 13 located between the rods 8 and preferably carried by the upper arbor. A second pigtail guide 14 is carried by the upper arbor and is located at a point somewhat to the rear thereof. Above the upper arbor is a pigtail 15 carried by the bracket 9 and located between the rods 8 substantially as the pigtail 13. The bracket 9 carries a second pigtail 16 which is located to the rear somewhat in the same manner as the pigtail 14. The pigtails 14 and 16, when looked at from the front of the machine, are slightly displaced so as to be on opposite sides of a vertical plane passing between the rods 8.

The cones upon the creel are so wound that their inner and outer ends are both free and exposed. In creeling the machine, two cones are placed upon the lower arbor, the outer end of the thread upon one cone 100 being tied to the inner end of the thread upon the other cone. The free outer end is then passed through the pigtail 13, pigtail 14 and beneath the horizontal guide bar 17, beneath the guide bar 18 in the trough 19, 105 over and between the rolls 20 and 21, and to the bobbin 22 after passing through the spinning ring (not shown). Similarly connected bobbins are placed upon the upper arbor, the free end of the yarn being passed 110

through the pigtails 15 and 16 and beneath the guide rods 17—18 and through the rolls 20—21 to the bobbin 22 in a similar manner. The pigtails 13 and 14 being each in the same relation to the two cones 11 and 11', whose yarns they guide, act to guide the yarn from one cone and then from the other without interruption. The pigtails 15 and 16 guide the yarn from the bobbins 12—12' in a similar manner. The pigtails 14 and 15 being in different transverse planes, guide the two threads of yarns from the two sets of bobbins so as to keep them separate until they pass beneath the rods 17 and 19 and to the rolls 20 and 21. When a cone has been exhausted, the yarn is automatically taken from the second cone of the same arbor, whose outer end is connected to the cone about to be exhausted. When a cone is exhausted the attendant replaces that cone by a fresh cone, connecting its outer end to the inner exposed end of the remaining cone so that the operation of the machine is not in any way interrupted during the providing of a new supply. The adding of a new cone is facilitated by the forward movement of the creel to which the cone is to be supplied and for that reason the creel is provided with the capability of being moved forwardly in the manner above described. After the new cone is supplied with the creel in forward position, the creel is moved to its normal vertical position, as shown in Fig. 1.

In order to increase the capacity of the machine, I alternate the arbors of adjacent creels so that the lower cones of one set of creels lie in a horizontal plane between the horizontal planes occupied by the cones of the adjacent creels. This is clearly shown in Fig. 2. By this alternation I am able to accommodate as large as seven inch cones in the series of creels although two adjacent creels occupy only a four and a half inch space.

The supporting arms of the arbors have pins 23 set at an angle to the uprights so that the cones of the two arbors are inclined toward the pigtails 13—15 respectively in order that the yarn from the bobbins carried by the arms may easily feed through those pigtails. The thread connecting two bobbins upon one arbor should pass between the rods 8 of its creel so that the yarn can be taken from the two bobbins successively. 24 are adjusting screws.

By this construction, as above stated, I obtain a machine which can be run continuously. Inasmuch as when properly operated there are no free moving ends of yarn, and inasmuch as the threads of any one creel by reason of the described location of the pigtails 14 and 16 are kept well apart from each other until they pass through the rolls 20 and 21, there is no interference between the

two threads from the same creel or any lashing of one thread of yarn by the free end of another. The forward movement of the creels for providing an additional supply, does not interfere with the thread running from such forwardly moved creel. A further advantage of my invention is that double knots or knots of double ply are avoided.

As will be evident to those skilled in the art, my invention permits of various modifications without departing from the spirit thereof or the scope of the appended claims.

What I claim is:

1. In a creel the combination of a series of upwardly extending carriers having their upper ends independently movable forwardly and rearwardly in fixed vertical planes, a plurality of cone supporting members supported by each carrier one above the other, and a guide above each of said members.

2. In a creel the combination of a series of upwardly extending carriers independently movable forwardly and rearwardly in fixed vertical planes, a plurality of cone supporting pins supported by each carrier one above the other, said pins being on the same side of said series, those on one carrier being at different heights from those on adjacent carriers, and said carriers being separated by a distance less than the diameter of a full cone, and a guide above each of said pins.

3. In a creel the combination of a series of upwardly extending carriers independently movable forwardly and rearwardly in fixed vertical planes, a plurality of cone supporting pins supported by each carrier one above the other, said pins being on the same side of said series, those on one carrier being at different heights from those on adjacent carriers, and said carriers being separated by a distance less than the diameter of a full cone, a guide above each of said pins, and additional pins supported by said carriers on the other side of said series at the same heights as their said first mentioned pins, the pins of the same height on each carrier being inclined toward each other.

4. In a creel the combination of a series of upwardly extending carriers independently movable forwardly and rearwardly in fixed vertical planes about a pivot at the lower end of each carrier, a plurality of cone supporting members supported by each carrier one above the other, and a guide above each of said members.

5. In a creel the combination of a series of upwardly extending carriers independently movable forwardly and rearwardly in fixed vertical planes about a pivot at the lower end of each carrier, a plurality of cone supporting members supported by each car-

rier one above the other, a guide above each of said members, and means for locking said carriers in upright position.

6. In a twister the combination of a series of upwardly extending carriers having their upper ends independently movable forwardly and rearwardly in fixed vertical planes, a plurality of cone supporting members supported by each carrier one above the other, a guide above each of said members, and a plurality of supplemental guides carried by each carrier, each supplemental guide being out of line with the thread passing from any other supplemental guide on the same carrier.

7. In a twister the combination of a series of upwardly extending carriers having their upper ends independently movable forwardly and rearwardly in fixed vertical planes, a plurality of cone supporting members supported by each carrier one above the other, a guide above each member, a plurality of supplemental guides carried by each carrier and moving forwardly and rearwardly therewith, and a fixed guide for receiving threads from each of said supplemental guides of each carrier, each supplemental guide being out of the line connecting the other supplemental guide and said fixed guide.

8. In a creel the combination of a series of upwardly extending carriers independently movable forwardly and rearwardly in fixed vertical planes, a plurality of cone supporting pins supported by each carrier one above the other, said pins being on the same side of said series, those on one carrier being at different heights from those on adjacent carriers, and said carriers being

separated by a distance less than the diameter of a full cone, and a guide above each of said pins, and additional pins supported by said carriers on the other side of said series at the same heights as their said first mentioned pins, the pins of the same height on each carrier being inclined toward each other, each of said carriers having two upright members spaced apart to permit the passing of the thread from both of said cones successively, the two upright members of any one carrier being in the same plane as the upright members of the other carriers and both acting to support each of the pins of the carrier to which they belong.

9. In a creel the combination of a series of carriers having upwardly extending portions and at their bases rearwardly extending portions, a support for said carriers to which the rear ends of said rearwardly extending portions are pivoted so as to move in vertical planes, and cone carriers mounted one above the other on said upwardly extending portions and guides supported by said carriers above each of said cone-carriers.

10. In a creel the combination of a series of carriers having upwardly extending portions and at their bases rearwardly extending portions, a support for said carriers to which the rear ends of said rearwardly extending portions are pivoted so as to move in vertical planes, cone carriers mounted one above the other on said upwardly extending portions and guides supported by said carriers above each of said cone-carriers, and locks for holding said upwardly extending portions in upright position.

RICHARD H. COOK.
